UNITED STATES PATENT OFFICE.

JOHN V. RICE, JR., OF BORDENTOWN, NEW JERSEY, ASSIGNOR TO RICE GAS ENGINE COMPANY, OF BORDENTOWN, NEW JERSEY, A CORPORATION OF NEW JERSEY.

OSCILLATING INTERNAL-COMBUSTION ENGINE.

Application filed July 3, 1920. Serial No. 393,946.

To all whom it may concern:

Be it known that I, JOHN V. RICE, JR., a citizen of the United States, and resident of Bordentown, in the county of Burlington and State of New Jersey, have invented certain new and useful Improvements in Oscillating Internal-Combustion Engines, of which the following is a specification, reference being had therein to the accompanying drawing.

My present invention refers to the general class of internal combustion engines, and to the special subdivisions of the same known as two-cycle and oscillating cylinder.

The oscillating cylinder type of gas engine possesses many advantages over the common and well known reciprocating, non-oscillating engine, particularly with reference to economy of space and weight coupled with high efficiency. In this type of engine a cylinder or a plurality of cylinders are mounted on gudgeons or trunnions, on which they are enabled to sway to and fro through a small arc, so as to enable the piston rod or rods to follow the movements of the crank to which they are directly connected, without the intervention of any other mechanism, such as correcting rods, etc., said piston rod or rods having a rigid connection with the piston, and sliding through a stuffing box in the end of the cylinder. One or more of the trunnions for each cylinder will be made hollow to allow of the admission therethrough into the cylinder of the explosive mixture from its source of supply. The valve mechanism, the chambers for the preliminary compression of the charge, and other essential features, can in this type of engine be arranged compactly together, so that everything is in a small compass, and the advantages that are gained by the oscillating cylinder construction of the steam engine are secured with equal effectiveness in the construction of an internal combustion engine. This is found, for example, to be so in the facility with which I arrange in some leading forms of the invention to introduce the explosive mixture for all the charges at the same end of the cylinder, (though of course it may be introduced at both ends) and am able to locate a compression chamber in one end of the cylinder, beyond the piston, for compressing the charge preliminarily for one

explosion, and another compression chamber in the other end of the cylinder, beyond the piston, for compressing the charge preliminarily for the next explosion, the partially compressed charges being carried from said end chambers into the firing chambers, where they are again and finally compressed before being exploded. I am able also to introduce the charge through ports running entirely around the piston, and also to exhaust through ports running entirely around the piston, that is to say to use a very large inlet and a very large outlet, whereby a large charge is quickly and completely introduced and whereby also a thorough and adequate scavenging is attained. Besides these points many others will appear as belonging essentially to and resulting from the making of the engine of the oscillating-cylinder two-cycle type.

An important feature of my invention lies in the piston, which is more or less elongated or extended and is differential in character, to correspond with the differential design of the cylinder; and the piston is provided with ports or passages running through the same from end to end, or thereabouts, and allowing communication between the end primary compression chambers and the explosion chambers, said ports or passages being capable of very great changes in form or plan. One form of this piston shown and described has hollow heads and tubes connecting the heads. But whether this particular form be employed, or many others, or whether the whole piston is cast in a single piece with hollow recesses, ports and passages running through same for the purpose stated, it will be seen that these tubes or ports will absorb much of the heat caused by the explosions, thus enabling the piston to keep comparatively cool and to keep down the temperature in the firing chambers, so that in this form all the power can be utilized and none is wasted or lost by the excessive generation of heat energy, for there are these cool currents of the new mixture flowing through the piston all the time, through the tubes or ports, and taking up more or less of the heat. Thus the tubes or ports take the place of the hot spot in certain other forms of combustion engines. It will also be seen that the construction of the engine locates the trunnions and piston rods away from the heat—

which is a decided advantage. And obviously the engine may have two-port or three-port cylinders.

Although the invention is chiefly designed as an oscillating cylinder engine, yet it will be understood that I do not wish to be restricted to the oscillating character, inasmuch as it is possible to arrange cylinders and pistons so that they may function as in the ordinary reciprocating explosive engine, having no rocking support, the same being possible through the modifications which can easily be had of the piston rod, the valve devices and the various chambers and other parts, retaining many of the important and leading features of the oscillatory construction and only omitting those which belong distinctively to the oscillating cylinder type. It will further be seen that whether the oscillating or non-oscillating type is employed, there may be one or more cylinders arranged in relation to the same crank-shaft and supported in a suitable frame for enabling them to discharge their full functions in operative relation to each other.

The object of the invention, therefore, is fundamentally to provide a simple, convenient and effective construction, whereby economy and ease of operation may be attained, with little likelihood of breakage or disrepair, and by which also the development of a large amount of power may be secured. The invention may therefore be said to consist essentially in the construction, arrangement and combination of the various parts, and in various details and peculiarities of the same, substantially as will be hereinafter more fully described and then pointed out in the claims.

40 In the accompanying drawings illustrating my invention:

Figure 1 is a vertical longitudinal section of my improved internal combustion engine, showing the piston at the upper or outer limit of its stroke.

Figure 2 is a horizontal sectional plan view on the line 2, 2, of Figure 7.

Figure 3 is a sectional elevation on the line 3, 3, of Figure 2.

50 Figure 4 is a vertical section, similar to Figure 1, on a larger scale, and indicating fewer parts, and showing the piston at the limit of its stroke opposite to that shown in Figure 1.

55 Figure 5 is a horizontal section on the line 5, 5, of Figure 4.

Figure 6 is a horizontal section on the line 6, 6, of Figure 4.

Figure 7 is a side elevation with certain 60 parts sectioned, the view showing the oscillating character of the engine.

Figure 8 is a detail view in plan of one of the wire gauze rings.

65 Figure 9 is another detail of a part of the same.

Figure 10 is a vertical longitudinal section similar to Figure 1, of a modified form of the engine, showing a single-acting instead of a double-acting engine.

Figure 11 is a sectional side elevation of 70 the upper part of the same.

Figure 12 is a horizontal sectional view on the line 12, 12, of Figure 10.

Similar characters of reference designate corresponding parts throughout the different views of the drawing.

The main frame of an engine of this type is built so as to permit the pendulous support of the cylinders, of which there will usually be a plurality, all applying their power 80 to the same crankshaft. As an example of frame construction, the same being suggestive merely and without any intention of being confined thereto, I have shown the standards or uprights 15, between which is a cylinder 1, or a series of similar cylinders, hung in a vibratory fashion, on trunnions 44 and 47 (see Figure 2), with suitable ball bearings 46, in the top portion of the standards 15, there being cap plates 45 or the like cov-

ering the said bearings and securely bolted or otherwise held in place. One or more of the trunnions of each cylinder is hollow, as trunnion 47, to admit the explosive mixture into the engine, and is entered by the 95 supply pipe 26, which may also connect with the trunnion of the next adjacent cylinder (not shown), the mixture flowing to pipe 26 through the connecting pipe 27 which leads from the carburetter and source of supply. 100 At the base of the engine moreover is the main crankshaft 14 having crank pin 13, to which the piston rod 10 is connected, it being obvious that this shaft will have as many cranks as there are cylinders, and that the connection of the piston rods with the cranks is direct without the intervention of any other mechanism. The crankshaft is enclosed within the lubricant-filled crank casing 11. In order to keep the same tight 105 at the point where the piston rod 10 enters the casing 11 and allow the rod the necessary range of movement during the swing of the cylinder I provide the cylinder with a curved plate 12 which covers an opening 71 in crank casing 11 and slides on the edge of this opening so as to prevent the escape of oil, said plate having a central sleeve 72 that telescopes with a boss 73 on the lower head of the cylinder, in connection with

110 which it adjusts itself and is held by an enveloping spring 23 so tensioned that plate 12 may be held securely over opening 71. There is also a packing gland 24 for the piston rod 10, to effect a tight joint, this gland being within the sleeve 72 and boss 73, and being capable of being loosened or tightened and held as desired by a catch 25. In this way a stuffing box or packing gland makes a tight joint for the rod 10.

At a suitable point alongside of the main frame is the stationary exhaust pipe 18 for carrying off the waste products of combustion, and this has a branch pipe 20 for each cylinder, with which branch pipe telescopes a pipe 19 which vibrates with the swinging cylinder, a tight joint between the moving parts being kept at all times by means of the packing gland 21. See Figure 6. The 10 exhaust outlet pipe 19 leads from the central portion of cylinder 1 where is situated the circular exhaust passage 17 and exhaust port or ports 22, as shown particularly in Figure 6, and hereinafter more fully explained, it being clear that the arrangement 15 of ports may be greatly modified without varying from the design of a large exhaust outlet at the centre of the cylinder that will function on each stroke and after each explosion, there being a single common exhaust outlet for both explosion chambers.

I will now proceed to describe the construction and operation of the cylinder 1 and its appertenant parts, it being understood 25 that the engine may be single or multi-cylinder in construction, and that where there are several cylinders, they will be duplicates of the one I am describing; but in the drawings I have only thought it necessary to 30 show a single cylinder, in order to impart the fullest understanding of the invention. Such cylinder is double-acting, compresses and fires at each stroke, and hence generates great power.

Cylinder 1 may be of any specific construction, dimensions and proportions. Its cooling system may use water or other liquid, a fan, or any other means for the purpose, but I preferably build it with a 35 multiplicity of radiating fins or flanges 1^a, which cover the surface, so as to avoid some of the objections incidental to water jackets and the like, said flanges being properly proportioned to provide the radiating surface 40 necessary for the amount of heat generated in the operation. The cylinder 1 has an upper head 1^d and a lower head 1^e. Such cylinder may be made in two castings B and C which are flanged to engage at the middle 45 of the cylinder, the upper casting B having lugs b, into which the vertical rods 16, 16, are screwed, and the lower casting C having lugs c through which said rods pass, their ends having thereon nuts 1^f which screw up 50 tightly against the said lugs c, so that in this manner the sections B and C of the cylinder are united by the tie-rods 16, 16, a pair of the same being usually sufficient to hold them closely together.

The bore of the cylinder 1 is of smaller diameter at the upper and lower ends than it is in the middle portion, its differential character in this respect corresponding to the differential piston 4 which reciprocates 65 within the cylinder 1. The middle and

larger portion of the cylinder furnishes the two explosion chambers A and D between and in which the widest part 5 of the piston operates, while in the upper end of the cylinder above piston 4 is a chamber E for the 70 primary compression of the mixture on the upstroke, and in the lower end of the cylinder below piston 4 is another chamber F for the primary compression of the charge on the down stroke of the piston, the terms 75 "above" and "below" and the like, as used here and elsewhere, not being terms of limitation but merely of explanation of the particular example.

The piston 4 is of the differential type, as 80 stated, having upper head 6, and lower head 7, and intermediate section 5, which latter is of larger diameter than the heads 6 and 7. Heads 6 and 7 are similar in construction and communicate with each other by the 85 tubes 8 and 9 that run alongside of each other within the cylindrical body of piston 4 and its central enlarged section 5. These heads 6 and 7 are hollow and each is dually pierced or compartmented, being partitioned 90 so that the compartments in the same head are non-communicating. In this way are provided two gas-charge-handling systems, one comprising chamber E, a part of head 6, tube 8, and chamber D, and the other a 95 distinct and non-communicating system comprising a part of head 6, tube 9, chamber F and chamber A; it being further noted that the piston is double-acting, that an explosion occurs at the end of each stroke and 100 drives it in each direction, and that although the mixture is (in this example) all taken into both systems from one and the same end of the cylinder on the down stroke, yet compression occurs on each stroke, as well 105 as ignition and exhaust.

I place special emphasis upon the feature of a trunk piston, having therein two distinct non-communicating channels or passages for the mixture, one channel conveying mixture from one compression chamber through the piston to one of the explosion chambers, and the other channel conveying mixture from the other compression chamber to the other explosion chamber, all the parts of the cylinder and piston being arranged in a compact and small compass, with compression chambers at the ends of the cylinder and central explosion chambers around the piston, the cellular or channeled construction of the piston thus enabling the heat of the explosions to be absorbed partially by the cooler charges coursing through the piston, and all these parts being susceptible of a wide diversity in their 110 115 120 125 specific structural detail.

The special construction of the head 6 is shown clearly in Figures 1 and 2, and the construction of head 7 is practically the same. Head 6 is circular and is a hollow 130

casting, having a passage 34 through it to connect the chamber E with the tube 8, and another separate and distinct passage 35 which connects the tube 9 with the lateral port or ports 33 which coincide at times with and receive gas from the cylinder port or ports 32, and at other times deliver into chamber A, as I shall presently specify, there being the partition 36, see Figures 1 and 2, forming part of the head casting, which partition separates the tubes 8 and 9 from each other and closes communication between tube 9 and chamber E. In the head 7 a similar construction exists, said head having a passage 37 from the tube 9 to the chamber F, while the tube 8 connects through passage 38 with a lateral port or ports that communicate at times with explosion chamber D, as I shall soon describe.

Observation should be made here of the important fact that the piston heads 6 and 7 are each provided with two sets of piston rings, each set preferably consisting of two rings, the said sets being designated 39 and 40, and in each head the lateral ports 33 are between the rings 39 and 40, and hence the joints around the ports are sealed more completely and their action is more perfect. Also, these ports extend entirely around the piston head, as shown in Figure 2, it being of course noted that in each piston head for half of the circumference the part 33^a of this lateral port, see Figure 2, is a semi-circumferential passage connecting with the passage 35 as in head 6, or the passage 38 as in head 7, but not at all times conveying mixture though filled therewith, but when connection is made with chamber A or D as the case may be, the entire port all around the piston head and comprising members 33 and 33^a performs the function of delivering the gas.

Each lateral port in the heads 6 and 7 consisting of members 33 and 33^a is preferably provided with a wire gauze protector, consisting of a split ring 41, carrying a gauze section 42 that occupies passage 33^a, and gauze sections 43 that occupy the port openings 33, see Figures 8 and 9, the function of this gauze protector or screen being to prevent the incoming charge from firing prematurely or causing a back explosion, or to prevent bad effects in the use of poor or slow burning mixtures. It may be said here that the enlarged central section 5 of the piston is also preferably supplied with two or more sets or pairs of piston rings to produce the best results in practice, though there is no port between the rings in this instance.

The wall of chamber E in the upper part of cylinder 1 is provided with inlet ports 32, with which the piston ports 33 register when the piston is at the upper end of its stroke as shown in Figure 1, see also Figure 2. On

the side of the cylinder 1 adjacent to trunnion 47 is a chamber 28 that receives mixture through the supply pipe 26 that enters trunnion 47, and there is also a passage 31 extending partly around the cylinder and in open communication with the cylinder ports 32. Between chamber 28 and passage 31 is interposed a check valve 29 operating in relation to a seat 29^a and provided with a stem and a closing spring 30. The suction of the engine will open valve 29 and draw a charge through the trunnion, into chamber 28 and past valve 29 into passage 31, and through ports 32 and 33 into the cylinder, but when compression occurs the check valve 29 will close down tightly upon its seat and remain there until again opened by the action of the vacuum in the cylinder.

The ports 32 not only deliver mixture through the piston ports 33 and 33^a into the head 6 and passage 35, and thence into tube 9, but the mixture is also drawn through ports 32 into the chamber E after piston head 6 uncovers ports 32 in its descent. Therefore when piston 4 is at the upper limit a charge enters through ports 32 and 33 into passage 35 and tube 9 and passes through passage 37 in head 7 and fills lower chamber F. As the piston descends the ports 33 shortly open into openings a^1 between ribs or braces a^2 into circular passage a at one end of explosion chamber A, (see Figure 5) and the charge which has received an initial compression in chamber F is now transferred through ports 33 and 33^a into chamber A, accelerating the ejection of the exhaust through the central exhaust ports 22 as soon as piston section 5 uncovers the ports 22, as shown in Figure 4. Moreover when the piston head 6 is released from ports 32 by passing below same as in Figure 4 the suction will draw in a charge into chamber E and thence it will fill tube 8 through passage 34. On the next upstroke this charge will receive an initial compression in chamber E, and as soon as the ports in head 7 open into the openings between ribs or braces d^2 and into circular passage d , in the lower end of explosion chamber D, (see Figure 1) the construction of the parts being the same as in the upper end of chamber A, at the same time that the piston section 5 uncovers ports 22 in its upstroke to relieve the exhaust, the charge in chamber E will be transferred to chamber D through passage 38 in head 7, and through the lateral ports in said head, so that this incoming charge will assist in driving out the exhaust products of combustion. The chambers A and D permit the mixture therein to be compressed with a secondary or final compression and then ignited by suitable means, as by ordinary spark plugs, of which I indicate examples at 48 and 49.

Referring further to the sets of ribs or

braces a^2 , between which are openings a^1 , that enter a circular passage a in the chamber A, and the similar construction in the chamber D I wish to emphasize the value of 5 the same. Obviously the spaces a^1 between ribs a^2 open not only into the passage a but quite directly into the interior of chamber A; and the same is true of spaces between ribs d^2 in chamber D. See Figures 4 and 10 5. The passages a and d might be omitted, but for the sake of lightness and more complete communication and propagation of the flame, it is preferable to have them. These 15 ribs a^2 and d^2 have their inner edges aligned accurately with the bore of the cylinder chambers E and F, and are slightly chamfered or inclined at their ends furthest from the cylinder chambers E and F. The purpose 20 of these chamfered ribs is to provide means that will engage the piston rings 39 and 40 and if they are slightly expanded automatically compress them to a diameter equivalent to that of the bore of chambers E and F and hold them in this position at 25 the moment of the gas delivery through ports 33 and 33^a by compressing them and guiding them surely into the bore of chambers E and F at the time when the parts of the engine are being assembled together. 30 The piston rod 10 has a screw-threaded end 67 which screws directly into the lower head 7 of the piston and is locked fast therein by a nut 68 or other device which screws tightly against the head 7; and, as already 35 noted, the packing gland 24 assists in making a tight joint where the rod 10 enters the crank casing 11. Thus the piston rod is rigidly connected to the piston and directly connected to the crankshaft 13, but as the 40 cylinder swings on trunnions, this construction is operative, and I am enabled therefore to utilize chambers in each end of the cylinder in which to compress the charges of air and gas, and to close both ends of the cylinder with heads, which would not be possible 45 if the piston rod 10 were pivotally connected with the piston, for it would have to pass out through the open lower end of the cylinder so as to give it room for a vibrating 50 movement. This enables the inlet and outlet ports to be located in the compact and convenient manner I have described, and to effectively function in the operation of the engine, whereby the whole construction is 55 simplified and cheapened; and the parts are few and combined together without loss of space or diminution in the free movement of any, enabling usually successful results to be attained in best type of engine that 60 can be selected for many purposes, one of which is aeroplane practice.

The foregoing description of the construction and arrangement of the various parts is sufficiently ample to make it unnecessary 65 to describe the operation in further detail.

If we assume that the piston is at the upper limit of its stroke, after being driven there by a firing of the charge in chamber D, the parts will be in the position shown in Figure 1, where exhaust from chamber D is 70 taking place through ports 22, while chamber D is being filled by a new charge on top of the outgoing exhaust through head 7 from tube 8 leading from chamber E. At the same time a previously introduced 75 charge in chamber A is receiving its final compression therein preparatory to its explosion which is about to occur; and also at this moment the lateral ports 33 in piston head 6 have been brought into communication with the inlet ports 32 and a charge is introduced into and through head 6 and by way of tube 9 to chamber F. A spark plug 48 will now explode the compressed charge in chamber A, which will drive the piston 80 down to the other end of its stroke and into the position shown in Figure 4. On its way down the mixture in chamber F is compressed until the head 6 brings its ports 33 and 33^a into communication with chamber 85 A when the said mixture will be delivered 90 into said chamber A, while simultaneously with such delivery the chamber A will open into exhaust ports 22 and the new mixture will flow in on top of the exhaust and help 95 to force it out; and while this is being done the charge that was introduced into chamber D is undergoing compression, and a new charge is being sucked in through the uncovered ports 32 into chamber E and tube 100 8 to receive a preliminary compression during the next upstroke of the piston. Thus cycle follows cycle, after the manner of a two-cycle engine, and with resulting effects of the character I have set forth. 105

It is easily possible to modify the construction of my engine and provide a single-acting form in lieu of the double-acting, without losing the advantages of the latter. An example of such modified form is shown 110 in Figures 10, 11, and 12. Here I employ elements which represent substantially one-half of those used in the double-acting engine. I use a similar cylinder 50 having fins or flanges 69, and having an upper head 54 and a lower head 55. In the cylinder 50 is a single firing chamber 62 instead of two chambers A and D, but the exhaust channel 52 is similar to channel 17. Channel 52 is entered by outlet ports 53. There are the 115 same exhaust pipes 18, 19, and 20. The lower end of cylinder 50 is of smaller diameter than chamber 62, and provides chamber 61 in which the smaller portion of the differential piston 51 operates, while its larger 120 upper end reciprocates in the chamber 62. A passage 66 runs through the hollow piston 51, to the lower head, which closes such passage and a chamber 70 is in communication therewith at the upper interior end of 125 130

cylinder 50. The head at the lower end of piston 51 is provided with lateral ports 64 which deliver into chamber 62 opposite ribs 63. At the upper end of cylinder 50 is a vertical supply pipe 57 for the gas, which is fitted with a check valve 56, and which receives a supply of fuel from the pipe 60 running through trunnions provided with ball bearings 58 at the top of standards 15, above which are the cap plates 59. The ports 64 are furnished with gauze or strainer devices 65, as before to prevent back firing and other disadvantages. The operation will at once be evident from this description of the construction. An explosion of the gas in chamber 62 will drive the piston 51 upward and when the wide part thereof uncovers the exhaust ports 53, the cylinder chamber 62 will be scavenged through said ports 53, and a new supply of gas will enter the chamber 62 through ports 64. The momentum of the engine will carry the crank over the dead centre and the piston will make a reverse stroke, during which it will create a vacuum and draw open the valve 56, filling interior space 66 in the piston. While this is filling with a new charge, the quantity previously introduced into the chamber 62 will be undergoing compression. When the explosion again occurs and the piston moves upward the check valve 56 will close and the mixture will be initially compressed in chambers 66 and 70, until the ports 64 open and the mixture enters the chamber 62; and the operation will proceed as before. It is evident also that there may be a plurality of similar single-acting cylinders acting upon the same crankshaft in a multi-cylinder engine, and producing successful results in a practical way.

The improvements herein set forth are applicable to either a two-port engine or a three-port engine, these terms being accepted and well known in the art. A two-port engine may be briefly described as one in which a check valve or its equivalent is utilized for the purpose of admitting a charge of mixture but preventing the back flow of the same, and in the example of mechanism set forth in this application such a construction is embodied. In a three-port explosive engine a check valve is not made use of but there is a sufficiency of ports to take care of the inlet and exhaust at the proper moment during the strokes and before and after each explosion to make it unnecessary to employ a check valve construction. I therefore suggest this very broad application of the principles of my invention. Furthermore it will be understood, as already hereinabove suggested, that many advantages accrue from the location of the various parts in respect to the saving of energy by the absorption of the heat and the prevention of loss in this way, the special mechanical feature by

which this is accomplished consisting in giving to the piston a cellular or shell-like form so that it may be passaged or ported, so that the cool stream of fresh mixture may pass through it from the initial compression chamber to the exploding chamber, for in this way not only is the undue heat of the exploding chamber absorbed and taken care of, but also the colder incoming mixture is more or less heated so that it is in better condition for compression and introduction into the exploding chamber. I also refer to the fact that the trunnions which convey the fresh mixture are located at a point remote from the explosions and consequently they are comparatively cool, safe and isolated, and further, the piston rod is placed at a distance from the explosion chamber and is also away from the heat, and thus the heat exerts no damaging effect upon the piston rod or rods or upon the trunnions on which the cylinder or cylinders rock.

It will also be kept in mind that although I have described one leading satisfactory and approved form of the invention in considerable detail, yet I do not wish to be restricted thereto and reserve the liberty of varying and modifying the details of the invention within wide limits and within the scope of the appended claims. I therefore, while insisting upon the leading features of the invention, claim the right to modify, rearrange or reconstruct the same along any lines in order to secure the best practical results at any time, and such changes as may be found necessary to do this will be covered by the claims which I have drawn.

Having thus described my invention, what I claim as new and desire to secure by Letters Patent is:

1. In an internal combustion engine, the combination of an oscillating cylinder having a compression chamber provided with a fuel inlet and having also an explosion chamber, a check valve in the compression chamber for admitting fuel during suction and preventing its escape during compression, and a piston surrounded by the explosion chamber and having one end contiguous to the compression chamber, said piston having one or more longitudinal transfer ports or passages for delivering the fuel mixture from the compression to the explosion chambers.

2. In an internal combustion engine, the combination of an oscillating cylinder having a compression chamber and a separate explosion chamber, a differential piston with one end operating in the compression chamber and an enlarged portion operating in the explosion chamber which surrounds said piston, means for transferring mixture through the piston from the compression to the explosion chamber, a piston rod attached rigidly to the piston and reciprocating and

swinging therewith, and a crankshaft to which the piston rod is directly connected.

3. In an internal combustion engine, the combination of an oscillating cylinder having a compression chamber and a separate explosion chamber, said compression chamber being provided with a valved fuel inlet which is automatically operative, and said explosion chamber having an exhaust, a differential piston operating in the compression chamber and having an enlarged portion operating in the explosion chamber which surrounds said piston, said piston being provided with a port for transferring the mixture from the compression to the explosion chambers, a piston rod rigidly attached to the piston, a crankshaft to which said piston rod is directly connected, and a pendulous support for the cylinder.
4. In an internal combustion engine, the combination of a cylinder having a compression chamber and a separate explosion chamber adjacent thereto, trunnions on which the cylinder rocks, a frame having bearings for said trunnions, means for conducting the fuel mixture through one of the trunnions, an automatic inlet for the compression chamber which receives the mixture from the trunnion and delivers it to said compression chamber, a differential piston operating in conjunction with the said chambers and having means for transferring the mixture through the same from the compression chamber to the explosion chamber.

5. In an internal combustion engine, the combination of an oscillating cylinder provided with trunnions on which it rocks, one of said trunnions serving as a fuel passage, a frame providing bearings for said trunnions, a compression chamber in the cylinder, a separate explosion chamber also in said cylinder, automatic fuel mechanism arranged in connection with the compression chamber for admitting fuel at the proper time to said chamber, a differential piston performing its functions in connection with the compression and explosion chambers, which latter chamber surrounds the piston, and means for transferring the mixture through the piston from the compression to the explosion chambers.

6. In an internal combustion engine, the combination of an oscillating cylinder having a compression chamber in one end, a separate explosion chamber adjacent thereto, a differential piston operating in the compression chamber and with an enlarged portion operating in the explosion chamber which surrounds the piston, a frame for supporting the cylinder in an oscillating manner, check valve mechanism for controlling the admission of a mixture into the compression chamber, and means for transferring the charge through

the piston from the compression chamber to the explosion chamber.

7. In an internal combustion engine, the combination of an oscillating cylinder having a primary compression chamber in one end and a separate chamber for secondary compression and ignition adjacent thereto, a differential piston having one end operating in the primary compression chamber and an enlarged section operating in the adjacent chamber, said latter chamber surrounding the piston and being provided with an exhaust and check valve means for admitting the charge during suction and automatically checking its outflow during compression, and means for transferring the charge through the piston from one end to the other so that it may pass from the primary compression chamber to the ignition and secondary compression chamber, a frame for supporting the cylinder in an oscillating manner.

8. In an internal combustion engine, the combination of an oscillating cylinder having a compression chamber and a separate explosion chamber, a differential piston operating in the compression chamber and having an enlarged portion operating in the explosion chamber which surrounds said piston, means for transferring the fuel mixture through the piston from the compression chamber to the explosion chamber, a piston rod rigidly attached to the piston, a crankshaft to which said piston rod is directly connected, a lubricant casing enclosing said crankshaft and having an opening through which the piston rod plays, and an automatically adjustable cover for said opening carried by the cylinder.

9. In an internal combustion engine, the combination of an oscillating cylinder having a compression chamber in one end and a separate explosion chamber adjacent thereto, a differential piston with one end operating in the compression chamber and an enlarged portion operating in the explosion chamber which surrounds said piston, means for transferring the fuel mixture through the piston from the compression to the explosion chambers, a piston rod rigidly connected to the piston, a lubricant casing surrounding said crankshaft and having an opening through which the piston rod plays, a curved sliding plate which covers said opening and vibrates during the movement of the engine, said plate having a sleeve engaging the cylinder and resilient means interposed between the plate and the cylinder for keeping the said plate tightly upon the opening in the casing.

10. In an internal combustion engine, the combination of a cylinder having compression chambers in each end and explosion chambers intermediate the compression

chambers, a differential piston operating in connection with said chambers and having ports or recesses to permit the passage of the mixture from the compression chambers 5 to the explosion chambers, a frame for supporting said cylinder in an oscillating manner, said frame receiving trunnions or projections from the cylinder, and means for delivering the mixture through one of said 10 trunnions to said cylinder.

11. In an internal combustion engine, the combination of an oscillating cylinder having compression chambers in each end and explosion chambers intermediate the compression chambers, a differential piston operating in connection with said chambers and having two separate lines of ports and 15 passages for enabling the fuel mixture to pass between the compression chambers and the explosion chambers, inlet means for drawing the fuel mixture into the compression chambers, said means including a trunnion inlet and an automatic valve device, a piston rod rigidly attached to the piston, and a 20 crankshaft to which said piston rod is directly connected.

12. In an internal combustion engine, the combination of an oscillating cylinder having compression chambers in each end and explosion chambers intermediate the compression chambers, a differential piston having its ends operating in the compression chambers and its middle enlarged portion operating in the explosion chambers, said 25 piston being of elongated form and comprising hollow heads and tubular connections between them through which the charge is transferred from the compression chambers to the explosion chambers, a pendulous support for the cylinder and inlet means at one 30 end of the cylinder for introducing the charge, said inlet means having automatically operating closing means to prevent outflow of the mixture during compression at 35 said end of the cylinder.

13. In an internal combustion engine, the combination of a trunnion-supported oscillating cylinder having compression chambers in each end and explosion chambers intermediate the compression chambers, a differential piston having its ends operating in the compression chambers and its middle 40 enlarged portion operating in the explosion chambers, said piston being of elongated form and comprising hollow heads and tubular connections between them through which the charge is transferred from the compression chambers to the explosion chambers, a common exhaust for the explosion chambers, and inlet means for introducing the charge, said inlet means having automatically operating closing means to prevent outflow of the mixture during compression.

14. In an internal combustion engine, the

combination of an oscillating cylinder having compression chambers in the ends and dual intermediate explosion chambers of greater diameter than the compression chambers, a differential piston having its 45 ends of smaller section operating in the compression chambers and its middle portion of larger section operating in the explosion chambers, means for transferring the charge through the piston from the 50 compression chambers to the explosion chambers, inlet means for introducing at each stroke of the piston in one direction two charges of the mixture one for each compression charge, said means having automatically operating means for preventing outflow during compression.

15. In an internal combustion engine, the combination of a trunnion-supported oscillating cylinder having primary compression 55 chambers in each end and dual chambers for final compression and explosion intermediate the primary compression chambers, a differential piston having its ends operating in the primary compression chambers and its 60 middle enlarged portion operating in the final compression and ignition chambers, said piston comprising hollow heads and tubular connecting parts, arranged so that two systems for fuel reception compression 65 and explosion are provided, one consisting of a primary compression chamber and a final compression chamber communicating with each other through the piston, and the other system consisting of the other primary 70 compression chamber and the other final compression chamber in communication with each other through the other channel in the piston, together with inlet means for the fuel having the function of delivering 75 the same at each stroke of the piston in one direction and being closed against admission during each opposite stroke of the piston.

16. In an internal combustion engine, the combination of an oscillating cylinder having primary compression chambers in each end and dual chambers for final compression and ignition intermediate the primary compression chambers and of a greater diameter than the latter, said final compression chambers having a common exhaust, a differential piston of smaller diameter at the ends which operates in the primary compression chambers and having a middle portion of larger diameter operating in the final compression and explosion chambers, said piston consisting of hollow heads and tubes connecting said heads together, said heads and tubes providing systems through 115 which the charges are carried from the chambers of primary compression into the chambers for the final compression and explosion, a pendulous support for the cylinder, inlet means at one end of the cylinder 120

125

130

for introducing charges at different periods at every stroke of the piston in one direction, but automatically closed against the admission of charges when the piston is 5 reciprocating in the opposite direction.

17. In an internal combustion engine, the combination of an oscillating cylinder having compression chambers in each end and explosion chambers intermediate the compression chambers, said explosion chambers having a common exhaust, an elongated piston with its ends operating in the compression chambers and its middle portion operating in the explosion chambers, said 10 piston comprising hollow heads and inter-communicating tubes, together with inlet means at one end of the cylinder for admitting one charge of the mixture to the interior of the piston and the next charge of 15 the mixture during the same stroke to the compression chamber adjacent to the same end of the piston, whereby each compression chamber is furnished with a charge during 20 each movement of the piston in one direction but not in the opposite direction, said 25

means having valve mechanism for preventing the admission and back flow of the mixture during said opposite strokes of the piston when compression is being had in the compression chambers.

18. In an internal combustion engine, the combination of a cylinder having compression and explosion chambers, a differential piston operating in connection with said chambers and provided with circumferential ports, said ports consisting of members adapted to register with cylinder ports, and with members which connect said registering members, so that at certain times when the mixture is incoming the flow of the latter will pass entirely around the piston but with the inlet or outlet effective only for a portion of the way around, while at other times the outlet is entirely around the circumference through the ports and their connecting members.

In testimony whereof I hereunto affix my signature.

JOHN V. RICE, Jr.
